COMBINED ASH RECEPTACLE AND AIR PURIFIER

John E. Gilbertson, 3209 Douglass, Des Moines, Iowa
50310, and Erwin W. Parr, 1345 McKinley, Des Moines,
Iowa 50315

Filed May 19, 1969, Ser. No. 17,199

Term of patent 14 years

Int. Cl. D27—03

U.S. Cl. D85—2

Fig. 1

Fig. 2

Fig. 3

Fig. 4

FIGURE 1 is a frontal perspective view of a combined ash receptacle and air purifier showing our new design; FIGURE 2 is a plan view thereof at an enlarged scale; FIGURE 3 is a side elevational view thereof as viewed from the left-hand side of FIGURE 2; and FIGURE 4 is a rear elevational view thereof as seen from the bottom of FIGURE 2.

We claim:

The ornamental design of a combined ash receptacle and air purifier, substantially as shown.
